[57] **CLAIM**

The ornamental design for a housing for a vacuum cleaner motor, as shown and described.

DESCRIPTION

FIG. 1 is a top, front and left side perspective view of a housing for a vacuum cleaner motor showing our new design;

FIG. 2 is a bottom perspective view thereof;

FIG. 3 is a left side elevational view thereof;

FIG. 4 is a right side elevational view thereof;

FIG. 5 is a top plan view thereof;

FIG. 6 is a rear elevational view thereof;

FIG. 7 is a front elevational view thereof; and

FIG. 8 is a bottom plan view thereof.

The features shown in broken lines in FIGS. 2 and 8 are for illustrative purposes only and form no part of the claimed design.

FIG. 1.FIG. 2.FIG. 3.FIG. 4.FIG. 5.FIG. 6.FIG. 7.

FIG. 8.
